UNITED STATES PATENT OFFICE.

JOHN J. BERRIGAN, OF CHICAGO, ILLINOIS, ASSIGNOR OF ONE-THIRD TO JOHN B. BERRIGAN AND ONE-THIRD TO KATHERYNE P. MALON, BOTH OF CHICAGO, ILLINOIS.

PRESS.

Application filed August 28, 1924. Serial No. 734,557.

To all whom it may concern:

Be it known that I, JOHN J. BERRIGAN, a citizen of the United States, residing at Chicago, in the county of Cook and State of Illinois, have invented a certain new and useful Improvement in Presses, of which the following is a specification.

This invention relates to press constructions, and particularly to the details of construction of a press, which while preferably hydraulic, may be operated by other means. One object of my invention is to provide a construction by means of which the bottom members of the press are mounted so as to facilitate discharge from the press after the pressing operation is complete and so as to prevent accidental discharge prior to that time. Another object is to provide a press having movable bottom members which are mounted in the press to permit some movement but to prevent accidental displacement. Other objects will appear from time to time throughout the specification and claims.

My invention is illustrated more or less diagrammatically in the accompanying drawing, wherein:

Figure 1 is a vertical cross section of a portion of the press in the open position before pressing has commenced;

Figure 2 is a similar view after pressing has been carried out.

Like parts are designated by like characters throughout.

A is a track member upon which the platen and partitions of the press are supported and adapted to move. There may be any suitable number of such tracks but I prefer to use one at each side of the press.

B indicates one of the side walls or casting members of the press by means of which it is enclosed.

C is one of the platens which is pressed laterally so as to move the press parts and to effect the pressing movement. As above stated it may be moved by hydraulic or any other suitable means. These are not shown here as their details form no part of the present invention.

Mounted within the press is any suitable number of partition members D. These members preferably consist of a central plate portion to each side of which is fastened a perforated plate D¹. These plates D¹ are spaced away from the plate D and therefore provide a drainage space through

which liquid matter pressed from the material being pressed may be discharged along the partition and out through the open bottom, indicated in each partition at D² D².

Mounted adjacent the bottom of each of the partitions is a supporting member E. There may be several of these members across the partition, but in the press I prefer to use three or four. They might, however, be replaced by a continuous member extending all or part of the way across the partition. The upper surface of this member is generally on the same plane as the upper surface of the track A.

Upon each of the members E is loosely mounted a bottom plate F. This plate extends all the way across the press and is practically the same width as the partitions. It is preferably provided with a somewhat sharpened upper edge F¹.

Secured to each of the partitions is a short chain G. This chain at one end is fastened to the partition and at the other end is fastened to a pin G¹ in the outer edge of the plate F. There are two such chains for each plate, that is, one at each end.

Secured to the partitions on each side adjacent their bottoms are chains H. These chains fasten the partitions together and space them, and prevent their displacement. Other chains H¹ H¹ are mounted at suitable points throughout the height of the partitions. In practice usually four chains are mounted on each side of the partition.

Although I have shown an operative device, still it will be obvious that many changes might be made in size, shape and arrangement of parts without departing materially from the spirit of my invention; and I wish, therefore, that my showing be taken as in a sense diagrammatic.

The use and operation of my invention are as follows:

The press as shown in Figure 1 is in the open position. In that position it is filled. The material may be put directly into the press or it may be put therein in bags or other containers. When the press is filled the weight of the material rests largely on the movably mounted bottom plates F.

As the press is closed the material presses against these bottom plates and there is a tendency to force the plates from their original inclined positions down to the hori-

zontal. If this tendency were not resisted the plates would fall to a horizontal position and would thus prevent the closing of the press. In so doing if the bottom edges of the partitions were not fastened by chains so that their distance apart is positively limited, the partitions themselves might be open to permit the downward movement of one or more of the bottom plates of the press, and thus the device will not operate satisfactorily.

In order to resist these tendencies, the partitions have chains between them and these chains positively limit the possible separation of the partitions. The inclined bottom plates of the press are also limited as to movement by means of other chains so that when the pressing movement commences, pressure on the bottom plates can not force them to the horizontal because, first, they themselves are fastened each to its next partition, and second, because the bottom of the partitions are fastened spreading, and thus the force exerted upon the bottom plate caused by forcing it to the horizontal, tends to force it to the vertical position as it is only free to move in that direction. Thus as the press is closed the bottom plate moves to the position shown in Figure 2, generally as the pressing is completed, moving to a complete vertical position and lying flat against the partition which its upper edge originally contacted. In this position, when the press is opened again for discharge, the bottom plate is still held in the vertical position and the contents of the press can be freely discharged from the bottom.

I claim:

40. 1. In a press, means for exerting pressure upon the contents of said press, a generally open bottom and a closing plate therefor adapted to support the contents of the press within the press, means for limiting the downward movement of said plate.
2. In a press, means for exerting pressure upon the contents of said press, a generally open bottom and a closing plate therefor adapted to support the contents of the press within the press, means for limiting the downward rotational movement of said plate.
3. In a press, means for exerting pressure upon the contents of said press, a generally open bottom and a closing plate therefor adapted to support the contents of the press within the press, means for limiting the downward movement of said plate, said means including a member fixed to a part of said press and to one side of said plate intermediate its ends.
4. In a press, means for exerting pressure upon the contents of said press, a generally open bottom and a closing plate therefor adapted to support the contents of the press

within the press, means for limiting the downward movement of said plate, said means including a support for one edge of said plate and including a member fixed to a part of said press and to one side of said plate intermediate its ends. 70

5. In a press, means for exerting pressure upon the contents of said press, a generally open bottom and a closing plate therefor adapted to support the contents of the press within the press, said plate adapted throughout the major portion of the pressing cycle to occupy an inclined position, and means for limiting the downward movement of said plate, said means including a member fastened to the side of said plate intermediate the upper and lower edges and fastened also to a part of said press. 75

6. In a press, a movable partition, means for exerting pressure upon the contents of said press, a generally open bottom and closing plates for said press on either side of said partition adapted to support the contents of the press within the press, and means for limiting the downward movement of said plates, said means including supporting means mounted on parts of said press adapted to support said plates, and additional means attached to parts of said press and attached to said plates intermediate their ends. 80

7. In a press, a movable partition, and means for exerting pressure upon the contents of said press, a generally open bottom, and closing plates for said press adapted to support the contents of the press within the press, said plates adapted during the major portion of the pressing cycle to occupy an inclined position, said plates being on either side of said partition, and means for limiting the downward movement of said plates, said means including supports for said plates upon which their lower edges normally rest, and additional means intermediate the upper and lower edges of said plates fastened to said plates and to parts of said press. 100

8. In a press, a platen adapted to be moved to exert pressure in the press, and partitions in said press, members joining such partitions and limiting their separation, and movable bottom members between said partitions adapted to close the bottom of the space therebetween and to support the contents of the press within the press, and being attached to one of the partitions by a member adapted to limit the movement of such bottom plate, and a supporting member on each partition upon which the lower edge of the said bottom plate rests. 105

9. In a press, a movable plate adapted to support the contents of the press within the press, said plate being mounted between opposite pressing members of said press and

adapted normally to lean with one edge against one of said members and the other edge against the other of said members and means for limiting the movement of the lower edge of said plate away from the pressing members which it normally contacts.

10. In a press, a movable plate adapted to support the contents of the press within the press, said plate being mounted between opposite pressing members of said press and adapted normally to lean with one edge against one of said members and the other edge against the other of said members and means for limiting the movement of the lower edge of said plate away from the pressing member which it normally contacts, said means including a member fixed to a part of said press and one side of said

20 plate.

11. In a press, a pair of platens and a movable plate mounted between opposite pressing members and adapted normally to lean with one edge against one of said members and the other edge against the other of said members and to retain the contents of the press within the press in combination with means for limiting the movement of the lower edge of said plate away from the pressing member which it normally contacts, said means including a chain fastened at one end to part of said press and at the other end to said plate there being one of such chains at each end of said plate.

Signed at Chicago, county of Cook and State of Illinois, this 23rd day of August, 1924.

JOHN J. BERRIGAN.
